UNITED STATES PATENT OFFICE.

CHARLES W. LEWIS, OF TAMPA, FLORIDA.

BASE-BALL GAME.

1,276,777.

Specification of Letters Patent. Patented Aug. 27, 1918.

Application filed April 1, 1918. Serial No. 226,033.

To all whom it may concern:

Be it known that I, CHARLES W. LEWIS, a citizen of the United States, residing at Tampa, in the county of Hillsborough and State of Florida, have invented certain new and useful Improvements in Base-Ball Games, of which the following is a specification.

This invention relates to an indoor base-ball game and has for its object the production of an amusing and attractive game board which may be very cheaply constructed and consequently placed upon the market at a minimum cost.

Another object of this invention is the production of a game board which is arranged in the form of a base-ball field and is provided with efficient means for permitting the players to easily determine the strikes and balls, as a ball is thrown across or by one side of the bat.

Other objects and advantages of the present invention will appear throughout the following specification and claims.

25 In the drawings:—

Figure 1 is a top plan view of the game board,

Fig. 2 is a section taken on line 2—2 of

Fig. 1, Fig. 3 is a section taken on line 3—3 of Fig. 1,

Fig. 4 is a fragmentary sectional perspective view of a portion of the game board, one of the ball receiving pockets being shown 35 thereon, and

Fig. 5 is a perspective view of the disk indicating a player.

By referring to the drawings, it will be seen that 1 designates the game board which 40 is provided with a ledge or frame 2 formed around the edge thereof, constituting an abutment for preventing the playing ball from falling from the board 1. The board 1 is provided with suitable lay-out markings 3 formed thereon following the usual design of a base-ball-field. A home plate 4 is located upon the base-ball-field in the usual manner together with the first, second and third base positions indicated by the 45 numerals 5, 6 and 7 respectively.

A plurality of ball receiving pockets 8 are also arranged upon the ball field in the usual position occupied by the respective ball players, the pockets representing the basemen, the 50 pockets being located adjacent their respective bases for the purpose of conveniently catching a

ball passing in close proximity to the base. A suitable catching pocket 9 is also located in the rear of the home plate 4 as shown clearly in Fig. 1 of the drawing. 60

A bat 10 is supported directly in the rear of the home-plate 4 and extends vertically, having its reduced lower end 11 fitting in the socket 12 formed in the board 1. In this manner the bat 10 may be easily supported 65 in a detachable position upon the board 1.

A strike indicating means, which may be known as an umpire is pivotally supported upon a pivot pin 13 and comprises a flat plate 14 having laterally extending wings 15 70 as shown clearly in Figs. 1 and 3 of the drawing. The pin 13 is supported directly in the rear of the bat 10 and the wings 15 of the plate 14 are adapted to extend upon opposite sides of the bat 10 so as to be engaged by a ball passing to one side of the bat at a proper distance whereby the plate 14 will be rotated upon the pin 13 and indicate to the players that the ball which is used in playing, has been thrown or shot by the bat 75 10 sufficiently close to be called a strike. Should the ball fail to hit the bat 10 or plate 14, the players will call the same a ball.

Each of the pockets 8 comprises a substantially triangular shaped body having the 85 side edges 16 thereof, secured to the body 1 or board 1 by means of the pins 17. Each pocket 8 is provided with an upwardly bulged portion 18 constituting a ball receiving pocket having a wide opened mouth 19 90 tapering toward the rear end of the pocket 8, as shown clearly in Fig. 4 of the drawing. A ball as indicated by the numeral 20 is used in playing the game, and the same may be either thrown toward the bat 10 or shot from 95 the fingers of the players, as is usual with such games.

In order that the method of playing the game may be clearly understood, the rules for playing the same are set forth as follows: 100

When persons play the game, one for each side or nine players representing a club, the pitcher throws or shoots the ball 20 from the pitcher's box 21 in the direction of the bat 10, thereby registering a ball, strike or hit. If the ball caroms off the bat 10 outside of the foul line, a foul strike (one) is registered and so on until the player is disposed of. If the player makes a hit, the ball will 110 roll between the pockets for a single, double, triple or home run. If a single hit is made,

the imaginary man, comprising a flat disk 22 is placed on first base as shown in Fig. 1, and so on according to the hit which is made.

5 If the ball goes into any pocket, the batter is out, but if the ball hits any pocket in the field, the ball will be supposed to be fielded and the batter is out. On the other hand, if the ball strikes an infield pocket and glances 10 to the out field, this would indicate a scratch hit and the batter takes first base.

If the ball misses the bat 10 and strikes the plate 14 (umpire) this indicates a strike. 15 If it misses both the bat 10 and the plate 14 this indicates a ball. If the ball hits and goes into the catching pocket 9, the player is out. If the batter gets four balls he goes 20 to first base. If batted ball hits in field pocket and stops or glances forward, the batter is out, but if the ball hits, glances and 25 hits the second pocket that would mean a double play. All batted balls going into pockets are fly balls and are called out.

Batted balls going between first base and 25 right fielder are one base hits, or third and left fielder between short stop and left fielder are two base hits. Should the ball pass between center fielder and left fielder this would be a three base hit, and between center fielder and second base, this would make 30 a home run. Should the ball hit the fence or if batted ball goes down inside the foul line and strikes either first or third base pocket and glance out of it, this would mean 35 a scratch hit.

The player 22 is a flat disk as above-stated in order to take up a minimum amount of space while resting upon the base and if the base is hit by the batted ball, the player is 40 out.

What is claimed is:—

1. A game of the class described comprising a board, a stationary bat carried by said board, an umpire plate, a pivot pin support-

ing said plate in the rear of said bat, said 45 umpire plate provided with a plurality of laterally extending wings adapted to extend upon the opposite sides of said bat for indicating strikes, and a plurality of pockets carried by said board and adapted to receive 50 a ball as the same rebounds from said bat.

2. A game of the class described comprising a board arranged in the form of a baseball-field, a bat carried thereby in the rear of the home plate, a strike indicating plate 55 pivotally supported in the rear of said bat, said strike indicating plate provided with laterally extending wings projecting upon either side of said bat and adapted to swing as a ball strikes the same after passing said bat, and ball receiving pockets carried by said board and arranged in the same relation as the players upon a ball field.

3. A game of the class described comprising a board arranged in the form of a baseball-field, a bat carried thereby in the rear of the home plate, a strike indicating plate pivotally supported in the rear of said bat, said strike indicating plate provided with laterally extending wings projecting upon either side of said bat and adapted to swing as a ball strikes the same after passing said bat, and ball receiving pockets carried by 60 said board, each pocket comprising a substantially triangular body secured around the edge thereof to said board, and said body provided with an upwardly bulged portion having a wide entrance mouth and tapering toward the rear end thereof. 75

4. A game of the class described comprising a board, a bat carried by said board, an umpire plate pivotally supported in the rear of said bat, means for receiving a ball as the same rebounds from said bat, and said umpire plate extending from the side of said 80 bat for indicating strikes. 85

In testimony whereof I affix my signature.
CHARLES W. LEWIS.
